US0D1059378S

(12) **United States Design Patent** (10) **Patent No.:** **US D1,059,378 S**
Bache et al. (45) **Date of Patent:** **** Jan. 28, 2025**

(54) **DISPLAY SCREEN HAVING A GRAPHICAL USER INTERFACE**

(71) Applicant: **Altria Client Services LLC**, Richmond, VA (US)

(72) Inventors: **Terry Bache**, Richmond, VA (US); **Ryan McGinley**, St Neots (GB); **Nicola Westgarth-Flynn**, St Neots (GB); **Eric Hawes**, Midlothian, VA (US); **Raymond W. Lau**, Glen Allen, VA (US); **Zack W. Blackmon**, Richmond, VA (US)

(73) Assignee: **Altria Client Services LLC**, Richmond, VA (US)

(**) Term: **15 Years**

(21) Appl. No.: **29/848,290**

(22) Filed: **Aug. 1, 2022**

(51) LOC (15) Cl. **14-04**

(52) U.S. Cl.

USPC **D14/485**

(57)

CLAIM

The ornamental design for a display screen having a graphical user interface, as shown and described.

DESCRIPTION

The FIGURE is a front view of a display screen having a graphical user interface, showing the new design.

The broken lines showing the display screen form no part of the claimed design.

The shaded areas of the drawing show a contrast in appearance.
